[57] **CLAIM**

The ornamental design for a pulley, as shown and described.

DESCRIPTION

FIG. 1 is a front elevational view of a pulley showing our new design with the rear and side elevational views being mirror images;

FIG. 2 is a top plan view thereof with the bottom plan view being a mirror image thereof;

FIG. 3 is a sectional view thereof taken along line 3—3 of FIG. 2;

FIG. 4 is a front elevational view of a second embodiment of the design shown in FIG. 1 with the rear and side elevational views being mirror images;

FIG. 5 is a top plan view thereof;

FIG. 6 is a bottom plan view thereof;

FIG. 7 is a sectional view thereof taken along line 7—7 of FIG. 5;

FIG. 8 is a front elevational view of a third embodiment

of the design shown in FIG. 1 with the rear and side elevational views being mirror images;

FIG. 9 is a top plan view thereof with the bottom plan view being a mirror image thereof; and,

FIG. 10 is a sectional view thereof taken along line 10—10 of FIG. 9.

FIG. 1

FIG. 2

FIG. 3

FIG. 4**FIG. 5**

FIG. 6

FIG. 7

FIG. 8**FIG. 9****FIG. 10**
